US00D996960S

(12) **United States Design Patent** (10) **Patent No.:** **US D996,960 S**
Hillard (45) **Date of Patent:** **** Aug. 29, 2023**

(54) **ADAPTER**

- (71) Applicant: **Mullet Tools, LLC**, Dripping Springs, TX (US)
- (72) Inventor: **Jacob Lee Hillard**, Plainville, KS (US)
- (73) Assignee: **Mullet Tools, LLC**, Dripping Springs, TX (US)

(***) Term: **15 Years**(21) Appl. No.: **29/824,899**(22) Filed: **Jan. 27, 2022**(51) LOC (14) Cl. **23-01**

(52) U.S. Cl.

(57) **CLAIM**

The ornamental design for an adapter, as shown and described.

DESCRIPTION

FIG. 1 is a top, front, left perspective view of an adapter showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a cross-sectional view at 8-8 in FIG. 4 thereof.

1 Claim, 7 Drawing Sheets(56)
